Patented Aug. 31, 1920.

INVENTOR
FRANK R. PETTITT
BY
C. J. Blake
ATTORNEY

UNITED STATES PATENT OFFICE.

FRANK R. PETTITT, OF PORTLAND, OREGON.

HEATER.

1,351,342.

Specification of Letters Patent. Patented Aug. 31, 1920.

Application filed January 29, 1919. Serial No. 273,896.

To all whom it may concern:

Be it known that I, FRANK R. PETTITT, a citizen of the United States, and a resident of Portland, county of Multnomah, State of Oregon, have invented certain new and useful Improvements in Heaters, of which the following is a specification.

My invention relates to heaters in general, and particularly to heaters adapted for use upon hydro-carbon motors for the purpose of heating the fuel intake manifold, the object being to aid in the starting of the motor by completely vaporizing the fuel gas.

I accomplish this object by means of the construction illustrated in the accompanying drawing, which is a part of this application for Letters Patent, like characters of reference indicating like parts throughout the several views of the drawing, and in which:

Figure 1 is a side elevation of my device applied to the motor manifolds.

Fig. 2 is a sectional elevation upon line 2—2 of Fig. 1.

Fig. 3 is a section upon line 3—3 of Fig. 1.

Fig. 4 is a perspective view of one of the manifold casing members.

Fig. 5 is a perspective view of the heater.

In general my device consists of a split casing adapted to surround the intake and exhaust manifolds of the motor, and a heater adapted to attach to said casing and provide heat therein.

Said casings surround the intake manifold 6 and the exhaust manifold 7, each portion of the casing consisting of a body 8 adapted to conform to the shape of the manifolds and to completely surround the same when the two portions of the casing are in place, alined flanges 9 adapted to closely surround the exhaust manifold when the casing is in place, and a depending flange 10 adapted to surround the depending portion of the intake manifold when the casing is in place.

When the two portions 8 of the casing are in place they are secured by encircling bands or clamping rings 11 upon each of the flanges 9 and 10, as shown in Fig. 1.

The heater 12 is an inclosed box like structure provided at its upper end with an open circular flange 13, which flange is adapted to slip over the assembled flanges 10 of the casing and receive its respective clamping ring 11 upon the outside thereof.

A vertically disposed slot 14 is provided

in said flange 13 to receive the lower end of the intake manifold and allow the same to protrude therefrom, as shown in Fig. 1. Said slot 14 also renders the flange 13 somewhat yielding so it may be readily compressed within its clamping ring 11 and thereby caused to securely clamp the flanges 10 of the two portions of the casing 8 together.

In the lower portion of the heater 12 is formed a fuel receptacle 15, shown in the drawings as adapted for liquid fuel, such as coal oil or the like, having a filling opening closed by a cap 16, and a lamp burner 70 17 disposed immediately beneath the open flange 13, and adapted to impinge its flame substantially upon the lower portion of the intake manifold, as shown in Fig. 1.

A spring hinged door 18 is provided in 75 the heater closing an opening 19 through which the lamp is reached for lighting the same.

Suitable openings 20 are provided in the casings 8 for the passage of the products of 80 combustion of the lamp, and also suitable openings 21 are provided in the heater for the admittance of air to the lamp.

My invention may be made of any size and constructed of any material deemed convenient and suitable for a device of this character, and while I have illustrated and described a form of construction and arrangement of parts found desirable in materializing my invention, I wish to include 85 in this application for Letters Patent all mechanical equivalents and substitutes that may fairly be considered to come within the scope and purview of my invention as defined in the appended claim.

Having disclosed my invention so that others may be enabled to construct and to use the same, what I claim as new and desire to secure by Letters Patent is:

1. In a heater for hydro-carbon motors, a 100 casing adapted to inclose the gas intake manifold of said motor; a downwardly projecting open flange upon said casing; a heater; an upwardly projecting flange upon said heater; and means to secure said flanges 105 together.

2. In a heater for hydro-carbon motors, a split casing adapted to inclose the gas intake and exhaust manifolds of the motor; horizontally disposed alined flanges upon 110 said casing adapted to be secured to the exhaust manifold; a downwardly projecting

flange upon said casing; a heater comprising a lamp and an oil font; an upwardly projecting flange upon said heater having therein a slot adapted to receive the lower end of the gas intake manifold; and means to secure said downwardly projecting and said upwardly projecting flanges together.

3. In a heater for hydro-carbon motors, a two piece casing adapted to inclose the manifolds of the motor, each member of said casing consisting of a body, a pair of oppositely disposed horizontally aligned half flanges, and a downwardly projecting half flange, the corresponding half flanges operating to form a whole flange adapted to encompass certain of said manifolds,

and means to clamp said casing in place upon said manifolds; in combination with a heater consisting of a flange adapted to receive therein each of said downwardly projecting half flanges, a combustion chamber, and a fuel receptacle.

In witness whereof I claim the foregoing to be my own. I hereunto affix my signature in the presence of two subscribing witnesses, at Portland, county of Multnomah, State of Oregon, this 17th day of Jan. 1919.

FRANK R. PETTITT.

Witnesses:
